UNITED STATES PATENT OFFICE.

WILLIAM S. HADAWAY, JR., OF NEW ROCHELLE, NEW YORK.

METHOD OF FORMING MATRICES.

Original application filed July 26, 1917, Serial No. 182,816. Divided and this application filed February 3, 1923. Serial No. 616,872.

This invention relates to new and useful improvements in method of forming matrices and its object is to provide a simple and efficient device for forming matrices from type or the like and to so improve the method of forming the matrices that they may be made better and more rapidly than has been possible heretofore and without injury to the type.

10 Matrix drying presses as heretofore used generally have a heated bed upon which the heavy form comprising linotype slugs, type, cuts and so forth of type metal are placed. Over this form, the sheet of soft papier mâché is placed with a plurality of wool blankets on top of it. These parts are then pressed together and the heat from the bed is conducted through the type and slugs to the matrix, the evaporated moisture from 15 which is slowly condensed and absorbed in the blankets. These become wet and have to be dried out for subsequent operations. The heat of the bed tends to soften the bottom of the type and slugs, and as the heat 20 is applied to the base of the form, instead of at the top where it is used, the temperature available for drying the matrix is very limited.

According to this invention, I do away 20 with the blankets or pads which have been used to condense and absorb the moisture from the matrix and provide a heated elastic pad, preferably a part of the press head, the surface of which acts as a condenser 35 for a brief period and then acts as a conductor for the moisture which is carried off at the edges of the pad with the heating vapor. I prefer to use superheated steam as the heating medium because it is capable 40 of taking up a great quantity of moisture. The type will not be overheated even though a large quantity of high temperature steam is applied to the pad, and the drying is effected in exceedingly short time. Provision 45 may be made for cooling the type bed for insuring the type against damage by heat.

I also provide a press head structure 50 which distributes the heated vapor or dry steam with substantial uniformity over the surface of the pad thereby insuring that the central portions of the mat will dry first as the moisture is driven out transversely through the pad. By this means a permanent flexible padding is secured which can

be kept dry and the form is preserved against 55 any possible damage by heat.

In order that my invention may be thoroughly understood I will now proceed to describe the same in the following specification, and then will point out the novel 60 features thereof in appended claims.

Referring to the drawings, Fig. 1 is a sectional elevation of a heating and drying press arranged and constructed in accordance with my invention and adapted for 65 practicing the same.

Fig. 2 is a bottom plan view of the upper press head of Fig. 1 with the surface coverings broken away to disclose the interior construction of the head.

Fig. 3 is a partial section on an enlarged scale showing in detail the formation of the surface pad of the upper head.

Figs. 4 and 5 are elevations at right angles to each other of a matrix drying press 75 embodying a movable press head arranged and constructed in accordance with my invention and adapted to act both as an elastic pad and as a heating and drying member.

Fig. 6 is a plan view of a form comprising 80 a chase with linotype slugs held therein by means of tapered quoins.

Fig. 7 is a plan view on a larger scale of a plurality of linotype slugs showing in 85 an exaggerated manner spaces which are left between them.

Fig. 8 is a sectional elevation of a linotype slug.

Referring particularly to Figs. 1, 2 and 90 3, 10 designates the base of a matrix press which, if desired, may be hollow as shown at 11 and provided with inlet and outlet conduits 12 and 13 for water cooling purposes. The movable press head is designated by 20 and this comprises a frame 21 having webs 22 which divide the frame into a plurality of rectangular pockets which are clearly shown in Fig. 2 and are designated by the reference number 23. Secured to the frame 20 above it is a distributing member 24 having a chamber 25 to which the hot vapor is supplied through the pipe 26 and a plurality of passages 27 having flaring openings 28 communicating respectively with the pockets 23.

The spaces or pockets 23 are filled with masses 30 of wire screen or some other suitable porous structure through which the hot

vapor may percolate. Beyond the webs 22 wire screens 31 or the like are stretched over the entire frame and outside of the wire screens 31 is an inner pad 32, the outer pad 33 and a surface covering 34 of cloth.

As shown in the drawings in Figs. 1 and 3, I prefer to utilize screens of coarser mesh at the top and build up screens of finer and finer mesh below them in order to combine

10 the strength and rigidity of the heavier screens with the small openings and elasticity of the finer screens. The pads 32 and 33 and the surface covering 34 are porous so that the hot vapor or steam which is admitted to the pockets 23 percolates through the pad after it passes through the screen pads.

The press head to which steam is supplied can be kept hot readily by supplying low 20 temperature steam through the pipe 26 and since the heat capacity of the head is not large it responds very quickly when high temperature steam is supplied. In other words, the standby losses are low and the apparatus may be kept in condition for use.

25 The form 40 comprises a chase 41 in which linotype slugs 42 or other desired pieces may be located as, for example, by tapered quoins 43. The linotype slugs 42 are usually constructed with spaced ribs 44 projecting from 30 one or both sides thereof and their lower ends are sometimes honeycombed or hollowed out as represented at 45 (Fig. 8). The ribs 44 cause the spaces 46 to be left between the slugs when they are put together.

35 The matrix drying press shown in Figs. 4 and 5 comprises a support 50 for the bed 10 and a yoke 51 which carries the head 20 movably. This yoke is arranged to bring the head down toward the bed 10 under pressure and a hand wheel 52 is provided for adjustment purposes.

40 I will now describe the operation of this apparatus. The form 40 is placed on the bed 10 (Figs. 1 and 5) and a mat 53 of moist papier mâché is placed over it. Superheated steam is passed through the head for a moment resulting in drying its pad. Then the head is lowered under pressure onto the 45 mat 53 and the flow of superheated steam is renewed or continued. Some of the moisture of the mat is squeezed out by the pressure and thus can fall freely through the spaces 46 of the form.

50 The heat of the head which is now in contact under pressure with the mat will cause the remaining moisture in the mat to evaporate and this evaporated moisture will be taken up by the superheated steam and carried off transversely at the edges of the pad. This operation will continue until the moisture is all removed after which the continued heat of the head will dry and bake the mat. By this means the high temperature 55 of the steam which is every effective in dry-

ing the mat is applied thereto directly and the rate of drying may be very greatly increased without danger of overheating the type. In fact, the type may be kept cool by the water jacket 11 of the bed upon which they rest. After the matrix is completed the head 20 is raised and is then in a perfectly dry condition ready for the next operation.

It is to be noted that the heat used to form the matrix is applied directly to the mat at the top of the form where it is most effective and not at the base where it has to be conducted up through the form to the mat. Thus a higher degree of heat can be used than with former methods.

An important feature of this invention is that when the matrix is formed, the application to the mat of heat on the surface away from the form causes this surface to harden first. The underside of the mat which comes in contact with the form remains soft and pliable for a longer time and is carried down into the fine delicate characters of the type and cuts and this operation is assisted by the fact that the upper surface has in the meantime become stiffened. Because of this fact a more perfect matrix is formed than with former practice because as heretofore made the parts of the mat which first come in contact with the heated type become hardened before they have fully permeated the parts of the type and cuts. With the present method although the proportional time for forming the working face of the matrix is greater than with former methods, the whole process is carried on and completed in a shorter period of time than has been possible heretofore.

To facilitate drying and hardening the 105 matrices an enveloping ring 60 of porous packing material may be placed on the bed 10 around the edges of the form in such position that it will be engaged by the head and thus enclose the space in which the form 110 is seated. As the type and slugs and cuts in the form have a definite and constant height, known as "type-high," a reasonably tight joint is easily secured and the porosity of the packing, permitting the vapor to escape 115 through it, permits sizing in the mat to be not only dried but subsequently heat treated and hardened.

This application is a division of an application Serial Number 182,816 filed July 26, 1917 and copending herewith on which Patent No. 1,551,149 was issued August 25, 1925.

Various advantages will suggest themselves to those skilled in the art and I intend only such limitations as are indicated 125 in the appended claims.

What I claim is:

1. The herein method of forming a matrix which comprises pressing a moist mat onto a form, and directing dry steam to the mat. 130

2. The herein method of forming a matrix which comprises supporting a form on an unheated bed, pressing a moist mat onto the form, and drying the mat while pressed by directing dry steam to the mat. 80
3. The herein method of forming a matrix which comprises pressing a moist mat onto a form, cooling the lower part of the form, and drying the mat while pressed by directing dry steam to the mat from the side thereof out of contact with the form. 35
- 10 4. The herein method of forming a matrix which comprises pressing a moist mat onto a form enclosing the form and mat and directing dry steam to the mat. 15
5. The herein method of forming a matrix which comprises supporting a form on an unheated bed, pressing a moist mat onto the form, enclosing the form and mat and drying the mat while pressed by directing dry steam to the mat. 40
- 20 6. The herein method of forming a matrix which comprises pressing a moist mat onto a form, cooling the lower part of the form, enclosing the form and mat and drying the mat while pressed by directing dry steam to the mat from the side thereof out of contact with the form. 45
- 25 7. The herein described method of forming a matrix which comprises placing a vertically porous form on an unheated bed, squeezing a moist mat onto the side of the form away from the bed, and directing a hot drying vapor onto the mat. 50
8. The herein described method of forming a matrix which comprises placing a vertically porous form on an unheated bed, squeezing a moist mat onto the side of the form away from the bed, enclosing the form and the mat, and directing a hot drying vapor onto the mat. 55
9. The herein described method of forming a matrix which comprises placing a vertically porous form on an unheated bed, squeezing a moist mat onto the side of the form away from the bed, and directing dry steam onto the mat. 60
10. The herein described method of forming a matrix which comprises placing a vertically porous form on an unheated bed, squeezing a moist mat onto the side of the form away from the bed, enclosing the form and the mat, and directing dry steam onto the mat. 65

In witness whereof, I have hereunto set my hand this 2nd day of February, 1923.

WILLIAM S. HADAWAY, JR.
